ANTISEPTICS

Louis J. Figg, Jr., Kingsport, Tenn., assignor to
 Eastman Kodak Company, Rochester, N. Y., a
 corporation of New Jersey

No Drawing. Application December 4, 1936,
 Serial No. 114,227

10 Claims. (Cl. 167—27)

This invention refers to antiseptics, and more particularly to antiseptics which are readily miscible with water. Its object is to provide dispersions of certain germicides, which dispersions can be readily mixed with water to provide antiseptic solutions of good wetting power.

It is known that certain phenolic compounds, namely ortho-phenyl phenol ($\text{HO.C}_6\text{H}_4.\text{C}_6\text{H}_5$), 2:4:5-trichlorophenol ($\text{C}_6\text{H}_5\text{Cl}_3.\text{OH}$), monochloro ortho-phenyl phenol ($\text{HO.ClC}_6\text{H}_3.\text{C}_6\text{H}_5$), 3-chloro-4-hydroxy diphenyl ($\text{HO.ClC}_6\text{H}_3.\text{C}_6\text{H}_5$), and 3-bromo-4-hydroxy diphenyl ($\text{HO.BrC}_6\text{H}_3.\text{C}_6\text{H}_5$), and their sodium salts, have germicidal properties. It is also known to disperse certain germicidal substances, such as the cresols, in soap solutions. However, the phenolic compounds belonging to the group just enumerated cannot be dispersed directly in soap solutions.

I have discovered that the phenolic compounds belonging to the group above enumerated are miscible with caustic-soluble hardwood oils, and that solutions of these phenolic compounds in hardwood oils can be readily incorporated in aqueous soap solutions to form dispersions which can be easily mixed with water to give antiseptic and fungicidal solutions of good wetting power, even for greasy surfaces.

The caustic-soluble hardwood oils which I employ are derived from heavy hardwood oils and tars having boiling ranges from 170° C. to 310° C. These heavy oils and tars settle out of the raw pyroligneous acid which results from the destructive distillation of hardwood, and are known as "settled tar". The caustic-soluble portion may be isolated as follows: A 5-15% solution of sodium hydroxide is added to the hardwood oil, with stirring, until the mixture becomes alkaline. The neutral oils separate out, and sodium salts of the acidic components of the wood oil are formed. The greater portion of the neutral oils is removed mechanically, and the remainder by steam distillation. These neutral oils are discarded. The solution of sodium salts is then treated with carbon dioxide gas to liberate the acidic components as oils, and to convert any free sodium hydroxide present to sodium carbonate and bicarbonate. The oils are then steam distilled from the mixture.

I give below two examples of the composition of antiseptic dispersions embodying my invention.

	Example 1	Example 2
	Percent	Percent
55 40% cocoanut oil soap emulsion	50	50
Ethyl alcohol	13	13
Caustic-soluble hardwood oil	30	32
Phenolic compound belonging to above-enumerated group	5	3
60 Essential oil	2	2

All proportions are given by weight. The phenolic compound is first dissolved in the caustic-soluble hardwood oil, and this solution is then mixed with the other ingredients. Obviously, the proportions of the ingredients may be varied widely, and I am not to be limited by the above examples except as indicated in the appended claims.

As much as 15% or even more of the phenolic compound may be used. The essential oil may be omitted if there is no reason for improving the odor of the composition. A small amount of potassium iodide or potassium bromide, for example 0.25 gram per 100 cc. of composition, may be added to prevent discoloration of the antiseptic composition in the light and air, as is described, in connection with liquid, antiseptic toilet soap, in the copending application of Louis J. Figg, Jr. and Edward E. Shaulis, Serial No. 100,037, filed September 9, 1936.

Of all the phenolic compounds belonging to the group enumerated above, I prefer to use monochloro ortho-phenyl phenol, because I have found that it is the most soluble in caustic-soluble hardwood oil.

What I claim as my invention, and desire to be secured by Letters Patent of the United States is:

1. An aqueous soap dispersion comprising caustic-soluble hardwood oil and an antiseptic phenol compound selected from the group consisting of ortho-phenyl phenol, 2:4:5-trichloro-phenol, monochloro ortho-phenyl phenol, 3-chloro-4-hydroxy diphenyl, 3-bromo-4-hydroxy diphenyl, and their sodium salts, the caustic-soluble hardwood oil acting as a dispersing agent for the antiseptic phenol compound.

2. An aqueous soap dispersion comprising caustic-soluble hardwood oil and monochloro ortho-phenyl phenol, the caustic-soluble hardwood oil acting as a dispersing agent for the monochloro-ortho-phenyl phenol.

3. Process of preparing an aqueous soap dispersion of an antiseptic phenol compound selected from the group consisting of ortho-phenyl phenol, 2:4:5-trichlorophenol, monochloro ortho-phenyl phenol, 3-chloro-4-hydroxy diphenyl, 3-bromo-4-hydroxy diphenyl, and their sodium salts, which comprises dissolving the antiseptic phenol compound in caustic-soluble hardwood oil and dispersing the resulting solution in an aqueous soap emulsion.

4. Process of preparing an aqueous soap dispersion of monochloro ortho-phenyl phenol, which comprises dissolving the monochloro ortho-phenyl phenol in caustic-soluble hardwood oil and dispersing the resulting solution in an aqueous soap emulsion.

5. An aqueous soap dispersion comprising caustic-soluble hardwood oil, an antiseptic phenol

compound selected from the group consisting of ortho-phenyl phenol, 2:4:5-trichloro-phenol, monochloro ortho-phenyl phenol, 3-chloro-4-hydroxy diphenyl, 3-bromo-4-hydroxy diphenyl, and their sodium salts, and a sufficient quantity of a potassium halide selected from the group consisting of potassium bromide and potassium iodide to keep the dispersion from darkening in the light and air.

10 6. An aqueous soap dispersion comprising caustic-soluble hardwood oil, monochloro ortho-phenyl phenol, and a sufficient quantity of a potassium halide selected from the group consisting of potassium bromide and potassium iodide to keep the dispersion from darkening in the light and air.

15 7. An aqueous soap dispersion comprising caustic-soluble hardwood oil, an antiseptic phenol compound selected from the group consisting of ortho-phenyl phenol, 2:4:5-trichlorophenol, monochloro ortho-phenyl phenol, 3-chloro-4-hydroxy diphenyl,

droxy diphenyl, 3-bromo-4-hydroxy diphenyl, and their sodium salts, and approximately 0.25 gram, per 100 cubic centimeters, of a potassium halide selected from the group consisting of potassium bromide and potassium iodide. 5

8. An aqueous soap dispersion comprising caustic-soluble hardwood oil, monochloro ortho-phenyl phenol, and approximately 0.25 gram, per 100 cubic centimeters, of a potassium halide selected from the group consisting of potassium bromide 10 and potassium iodide.

9. A solution, in caustic-soluble hardwood oil, of an antiseptic phenol compound selected from the group consisting of ortho-phenyl phenol, 2:4:5-trichloro-phenol, monochloro ortho-phenyl 15 phenol, 3-chloro-4-hydroxy diphenyl, 3-bromo-4-hydroxy diphenyl, and their sodium salts.

10. A solution of monochloro ortho-phenyl phenol in caustic-soluble hardwood oil.

LOUIS J. FIGG, JR. 20
